[57] CLAIM

The ornamental design for a curing oven for photopo-
lymerization, as shown and described.

DESCRIPTION

FIG. 1 is a front elevational view of a curing oven for
photopolymerization showing my new design;

FIG. 2 is a right side elevational view;

FIG. 3 is a left side elevational view; and,

FIG. 4 is a top plan view thereof.

The rear is conventional in appearance.

The broken line showings of electric cords in FIGS. 1
and 2 and vent openings in FIG. 4 are for illustrative
purposes only, and form no part of the claimed design.
